OPHTHALMIC INSTRUMENT STAND

Kenneth D. Maier, Mendon, N.Y., assignor to Bausch & Lomb Incorporated, Rochester, N.Y., a corporation of New York

Filed Jan. 2, 1963, Ser. No. 73,032

Term of patent 14 years

(Cl. D57—1)

FIG. 1 is a front perspective view of an ophthalmic instrument stand showing my new design, and

FIG. 2 is a rear perspective view thereof.

I claim:

The ornamental design for an ophthalmic instrument stand, substantially as shown.
